UNITED STATES PATENT OFFICE.

JOHN A. KNIGHT, OF AUBURN, MAINE.

PILLOW-SHAM FRAME.

SPECIFICATION forming part of Letters Patent No. 258,438, dated May 23, 1882.

Application filed March 15, 1882. (No model.)

To all whom it may concern:

Be it known that I, JOHN A. KNIGHT, of Auburn, in the county of Androscoggin and State of Maine, have invented certain new and 5 useful Improvements in Pillow-Sham Frames; and I do hereby declare that the following is a full, clear, and exact description of the invention, which will enable others skilled in the art to which it appertains to make and use the 10 same, reference being had to the accompanying drawings, and to letters of reference marked thereon, which form a part of this specification.

Figure 1 shows a front view of my apparatus attached to a bed and turned up so as to 15 hold the shams off from the pillows. Fig. 2 is a side elevation with the frame turned down over the pillows. Fig. 3 is a side elevation of the frame turned up as in Fig. 1. Fig. 4 is a detail showing the joint in the roll. Fig. 5 is 20 a detail showing the manner of holding the roll in position.

Same letters show like parts.

My invention relates to frames attached to the heads or head-boards of beds to support 25 and lift "pillow covers" or "shams," as they are called.

The invention consists in the combination of a roll, *a*, a spiral spring, *b*, a catch, *c*, two perforated ears, *d*, wire rods *e e'*, and cord *f*, as 30 hereinafter explained.

Before my invention rods or frames have been constructed and attached to beds to raise, let down, and hold either up or down the coverings or shams of pillows. My invention is 35 different from these in construction and in the combination of parts. The roll *a* extends across the head-board and has two journals, *g g'*. These work into the holes for their reception in the ears *d*. The hole *g''* is cut up through 40 to the edge of the ear, so that the roll can be taken off its bearings when the sham is to be cleaned. A spiral spring, *b*, presses the end of the roll opposite to the one at which said spring is located against the inner face of the ear. 45 The journal *g'* has the projection or catch *c*. When the roll is turned so as to lift the sham off the pillows and hold it up against the head-

board of the bed the projection *c* is pressed by the spiral spring *b* into the extension of the hole *g''*, and thus holds the roll turned up in 50 the manner referred to. When the roll is to be so turned as to allow the shams to cover the pillows the roll *a* is pushed so as to throw the projection *c* out of the extension of the hole *g''*, and the roll can then be revolved. 55

The pillow sham or shams are held extended over the frame *j*. This is composed of the parts *e e'* and *e'* and the cord *f*. The parts *e e'* consist of two wires twisted together and separated at the bottoms, so as to enter the roll, as seen at *o*, and thus make the rods firm in their position. At the outer ends they are formed into eyes *p*. The part *e'* is formed of three wires twisted together attached to the roll, as seen at *q*, and formed into the eye *p* at the top, 65 as seen in the drawings. The cord *f* is secured to the roll near each end of it, passing through the eyes *p*.

The sham is attached in any convenient manner to the roll at *r*. The roll, when required, is made so as to be capable of being lengthened, as shown in Fig. 4. It is so done by having it split a part of its length, in the manner seen in the drawing referred to. It is then cut into on opposite sides, as seen at *s*, 70 so as to divide the roll into two parts, as illustrated. The ends of the two split portions are fitted with ferrules *t*, so as to hold the two parts as they slide on each other, or when stationary. 80

What I claim as my invention, and desire to secure by Letters Patent, is—

The combination of the roll *a*, spiral spring *b*, catch *c*, ears *d*, wire rods *e e'*, and cord *f*, the same being made as herein set forth and attached to a bedstead, as described. 85

In testimony that I claim the foregoing as my own I affix my signature in presence of two witnesses.

JOHN A. KNIGHT.
